UNITED STATES PATENT OFFICE.

FERDINAND W. KROGH, OF SAN FRANCISCO, CALIFORNIA.

CENTRIFUGAL PUMP.

1,141,556.

Specification of Letters Patent.

Patented June 1, 1915.

Application filed August 17, 1908. Serial No. 448,974.

To all whom it may concern:

Be it known that I, FERDINAND W. KROGH, of San Francisco, State of California, have invented certain new and useful Improvements in Centrifugal Pumps, whereof the following is a specification.

My invention relates to the balancing of the impeller wheel whereby it is caused to float, as it were, in the liquid on which it is 10 operating, and end thrust is avoided.

To this end I provide one or more suction chambers opposite the suction supply of the pump to counterbalance the weight of the indrawn liquid—one of these chambers is 15 normally open and constitutes a communicating passage with a normally closed chamber which latter is opened by a movement of the impeller under the suction of the indrawn liquid, and is thereby thrown into 20 action to oppose said suction and return the impeller to its normal position. The normally open chamber is of smaller diameter than the suction supply, and the normally closed chamber is annular and surrounds the 25 open chamber, and is of greater diameter than the suction supply. As entrained gritty matter in the water pumped, rapidly cuts the moving parts, I apply a packing ring, and sometimes wearing rings also, to 30 control the leakage into said chambers from the discharge space of the pump.

In the accompanying drawings I have shown portions of two centrifugal pumps containing my invention.

35 Figure 1 is a sectional elevation of part of a pump with a horizontal shaft and a vertical impeller. Fig. 2 is a sectional elevation of part of a pump with vertical shaft and horizontal impeller.

40 In the figures; 1 is the casing.

2 is the suction opening.

3 is the suction pipe particularly shown in Fig. 1.

4 is the impeller.

45 5 is the impeller shaft.

6 are packing rings between the impeller and the casing.

7 are springs for pressing said packing rings against the casing.

50 8 are wearing rings between the impeller and the packing rings 6 and preferably attached to the impeller.

9 is the step-bearing of the vertical shaft pump.

55 10 is a cup containing lubricant for the step-bearing.

11 is a chamber formed in the casing and impeller, or either of them opposite the suction supply 2.

12 are channels maintaining an open communication of chamber 11, with the interior of the impeller.

13 is a normally closed chamber between the impeller and the casing and formed by recessing either or both of these parts.

60 14 is an annular flange on the impeller which closes against an adjacent bearing on the casing either by abutting against the latter, as seen in Fig. 1 or by sliding within the same as seen in Fig. 2, or otherwise.

15, are wearing rings on the impeller flange 14 where it contacts with the casing.

16, are similar wearing rings on the casing in position to contact with flange 14 or its wearing ring.

70 17, is the space within the casing at the side of the impeller on the suction side. 18, is the similar space opposite the suction side. These spaces 17 and 18 are in communication with the discharge of the pump—there

is therefore a pressure against the impeller in these spaces, and the radial dimensions of the spaces are gaged to balance the impeller as nearly as possible. Under the influence of the pressure more or less water

80 will leak from space 18 into chamber 13 and create a pressure therein as long as that chamber remains closed. Hence in a horizontal-shaft pump as in Fig. 1 the space 17

is approximately equal to space 18 and 80 chamber 13 combined, while in a vertical shaft pump, as Fig. 2 the space 17 is smaller so as to leave a surplus of pressure upward to help counterbalance the weight of the

shaft and the impeller.

90 In operation, the impeller being rotated creates a suction through opening 2. This tends to suck the impeller to that side and causes great friction and wear when not counteracted. The same force, however,

100 which causes the suction at 2 tends to create a vacuum in chamber 11. If now the impeller moves toward opening 2 the contacting points between flange 14 and the adjacent surface of the casing are separated and

105 the suction in chamber 11 is transmitted to chamber 13. These parts are so proportioned that the full suction of 11 and 13 combined is greater than that of 2 while the

110 suction of 11 alone is less than that of 2. The wheel then will oscillate between these two positions until it reaches a mean posi-

tion in which the suction from chamber 13 is just enough greater than the leakage into that chamber to place the impeller in equilibrium.

Obviously the above structure may be variously modified without departing from the spirit of my invention.

Having thus described my invention, I claim,

- 10 1. In a centrifugal pump the combination with the casing and the impeller therein, an intermittently closed pressure chamber in the impeller and an open face vacuum chamber in the casing, an annular outward projecting flange on said impeller abutting the outer edge of said vacuum chamber and adapted to form suction communication with said pressure chamber.
- 20 2. In a centrifugal pump the combination with the casing and the impeller therein, an annular pressure chamber in the impeller surrounding the hub thereof and a vacuum chamber in the casing surrounding the impeller shaft, an annular outward projecting flange on the impeller, forming the inner wall of the pressure chamber, adapted to establish communication between said cham-

ber and the vacuum chamber, and a removable wearing ring at the outward end of said projecting flange engaging corresponding 30 wearing ring on said casing.

3. In a centrifugal pump, the combination with the casing and the impeller therein, a suction inlet at one side of the impeller, a depression in the casing opposite said suction inlet forming a vacuum chamber around the impeller shaft, a series of channels in said impeller, permanently communicating said vacuum chamber with said suction inlet, an intermittently closed annular pressure chamber in the impeller around 35 said channels adapted to form a suction chamber by the lateral movement of the impeller and a flange in said impeller provided with a removable wearing ring adapted to open and close communication between the vacuum and suction chambers.

In testimony whereof, I have hereunto signed my name in the presence of two witnesses this 7th of August 1908.

FERDINAND W. KROGH.
